ATTORNEYS.

UNITED STATES PATENT OFFICE.

FLORENCE B. MYERS, OF MINNEAPOLIS, MINNESOTA.

BUILDING BLOCK.

1,410,588.

Specification of Letters Patent. Patented Mar. 28, 1922.

Application filed June 22, 1921. Serial No. 478,552.

To all whom it may concern:

Be it known that I, FLORENCE B. MYERS, a citizen of the United States, residing at Minneapolis, in the county of Hennepin and 5 State of Minnesota, have invented certain new and useful Improvements in Building Blocks, of which the following is a specification.

My invention relates to building blocks 10 and more particularly to building blocks of cement or other plastic material. An object is to provide a block of this character having structural features adapted to facilitate the building of a multiplicity of the blocks 15 into a wall. Another object is to provide a block so constructed that a wall may be readily and easily laid without the use of mortar and which wall will have a continuous passageway extending from top to bottom, and also horizontally, and adapted to 20 be filled with liquid cement for permanently holding the blocks together in the wall. Another object is to provide a block having air spaces and channels so arranged that when 25 the wall is laid there will be a continuous passageway therein extending from top to bottom, and also horizontally for passage of air whereby the wall will be effectively 30 ventilated, thus preventing the accumulation of moisture therein.

The full objects and advantages of my invention will appear in connection with the detailed description thereof and the novel features embodied in my inventive idea will 35 be particularly pointed out in the claims.

In the accompanying drawings, which illustrate the application of my invention,—

Fig. 1 is a top plan view of a portion of a wall made from my blocks and also showing the construction at one corner of the wall. Fig. 2 is an end view of one of my blocks. Fig. 3 is a longitudinal section on the line 3—3 of Fig. 1. Fig. 4 is a longitudinal section on the line 4—4 of Fig. 1 before puddled cement is poured in. Fig. 5 is a similar view showing the puddled cement in place. Fig. 6 is a transverse section on the line 6—6 of Fig. 1. Fig. 7 is a transverse section on the line 7—7 of Fig. 1 40 showing the wall provided with means for assisting in ventilation. Fig. 8 is a top plan view of a portion of a wall with the blocks laid the other side up from that shown in Fig. 1. Fig. 9 is a transverse section on the line 9—9 of Fig. 8 and showing the vertical passageways filled with cement. Fig. 10 is 45 a view similar to Fig. 9 showing a slight modification. Fig. 11 is a top plan view of a portion of a wall in which curved blocks are used for constructions such as silos. 50 My block is made of cement or other plastic material and, as shown in the drawings, embodies the same idea and arrangement in regard to air spaces and interlocking whether in the form of rectangular blocks, corner blocks or curved blocks. As 55 shown I provide a block having the two opposite side portions 10 and 12 connected by an intermediate portion 14, the latter portion being raised, as best shown in Figs. 2 and 6. The two side portions are provided with a pair of vertical air spaces 16 and the intermediate portion is provided with a vertical space 18 which, as shown, is oval in 60 form. The intermediate raised portion on its upper side has a pair of longitudinal ribs 20 and 22 adapted to extend up into the bottom of a superposed block so as to abut with shoulders 24 and 26 thereon. This provides for interlocking engagement of the 65 blocks vertically when they are laid up into a wall. The two portions 10 and 12 are provided at one end of the block with vertical recesses 28, and at the other end with corresponding projections 30. The projections 70 fit into the recesses 28 of the adjacent block lying in the same course when the blocks are laid up into a wall whereby the blocks are locked together horizontally. Between the ribs 20 and 22 the intermediate 75 portion is formed with a concave recess 32. The 80 projections 30 fit into the recesses 28 of the adjacent block lying in the same course when the blocks are laid up into a wall whereby the blocks are locked together horizontally. Between the ribs 20 and 22 the intermediate 85 portion is formed with a concave recess 32. It is, therefore, apparent that there will be 90 longitudinal passageways 34 as shown in Fig. 6 extending between the courses and these passageways will join all of the vertical spaces 18. The intermediate portion 95 of the block is further provided at each end with a semi-circular recess 36 so that when the blocks are laid the two recesses of adjacent blocks come together and form circular spaces 38. As will be apparent from Fig. 1, when the courses are laid in staggered relation in the usual manner spaces 38 of one course will lie directly underneath the oval spaces 18 of the superposed course. 100 The upper surfaces of the side portions 10 and 12 are provided with longitudinal grooves 40 and 42 so that when the blocks are laid the vertical spaces 16 will be connected by longitudinal passageways for circulation of air. Corner blocks are formed 105 as shown in Fig. 1 by providing a construc- 110

tion in which one end of the block is arranged at right angles to the other end. In this case one of the air spaces in the side portion 12 is omitted and a similar air space 17 is provided in the side portion 10' located at right angles to the side portion 10. In laying up a wall with my blocks a suitable base B is first provided and the blocks are laid upon this base and upon each other in superposed courses with the blocks in succeeding courses laid in staggered relation. The blocks will be held together both vertically and horizontally in the manner previously stated, and the use of mortar between joints 15 may thus be entirely dispensed with. When the wall has been completed, or at any time when considered desirable, puddled cement is poured into the openings in the intermediate portions of the blocks constituting 20 the upper course and this cement on account of the passageways connecting the openings in the manner previously described will flow into the openings of the intermediate block portions of the lower course. As is apparent from Fig. 5, this causes the intermediate portion of the walls to be of the nature of monolithic construction, it being noted that the cement fills the spaces 18 and 38 and the passageways 34. As shown in 25 Figs. 8 and 9, the blocks may be laid the other side up if found desirable. Fig. 10 shows a slight modification for use in case it is desired to point up the wall. Depressions 44 are formed at the upper and lower 30 edges of the blocks and these depressions if desired may be on both the inside and outside faces. After the wall is laid these depressions are filled in with mortar or cement. Fig. 7 shows how my wall may be adapted 35 for ventilation. A special block 46 is provided for the lower course. This block has a passage 48 connecting two air spaces of the inner and outer portions of the block, while the air space 16 nearest the inside of the 40 wall is provided with openings 50 which constitute a register. A similar block 52 is provided in one of the upper courses. In this block there is a passage 54 connecting two air spaces of the inner and outside portions of the block, while the air space nearest the outside of the wall is provided with 45 openings 56 which constitute a register. On account of this construction it is obvious that complete circulation of air is provided 50 through all of the air spaces of both the side portions of the blocks. In the form of invention shown in Fig. 11 the blocks are con-

structed in the same manner as previously described except that they are curved instead of being rectangular. Since this view 60 is similar to Fig. 8, the same reference numerals with the prime mark added are used.

I claim:

1. A building block having two side portions and an intermediate raised portion, 65 longitudinal ribs on one face of the block which limit the sides of said raised portion and enclose between them a concaved longitudinal recess extending from one end of the block to the other in said raised portion, and curved shoulders on the opposite face of the block with which ribs on adjacent blocks corresponding to the above mentioned ribs are adapted to fit, said shoulders being located outwardly from the two longitudinal 70 sides of said raised portion, each of said side portions containing two vertical air spaces positioned at equal distances from the two ends of the block and having a longitudinal groove along its middle on one face of the 75 block connecting said air spaces, said block having a vertical opening at its center and a vertical recess at the middle of each of its ends whereby vertical passageways will be formed in the wall when the blocks are laid 80 in staggered relation in courses.

2. A building block having two side portions and an intermediate raised portion, corresponding lugs and recesses on opposite 85 ends of said side portions, longitudinal ribs 90 on one face of the block which limit the sides of said raised portion and enclose between them a concaved longitudinal recess extending from one end of the block to the other in said raised portion, and curved shoulders 95 on the opposite face of the block with which ribs on adjacent blocks corresponding to the above mentioned ribs are adapted to fit, said shoulders being located outwardly from the two longitudinal sides of said raised portion, 100 each of said side portions containing two vertical air spaces positioned at equal distances from the two ends of the block and having a longitudinal groove along its middle on one face of the block connecting 105 said air spaces, said block having a vertical opening at its center and a vertical recess at the middle of each of its ends whereby vertical passageways will be formed in the wall when the blocks are laid in staggered relation in courses.

In testimony whereof I hereunto affix my signature.

FLORENCE B. MYERS.
